8 Claims. (Cl. 90—1.6)

This is a division of my application Serial No. 212,763, filed July 24, 1962, and now abandoned.

The present invention relates to gear finishing methods in general, and more particularly to improvements in mounting and positioning of the work holder with respect to the tool holder or vice versa in a gear shaving or another gear finishing machine. Still more particularly, the invention relates to improvements in a method of crossed-axes shaving of gear-shaped workpieces.

It is known to provide a gear shaving machine with a spindle which serves as a means for rapidly advancing one of the holders toward or away from the other holder and to utilize a cam which advances the movable holder toward the fixed holder when the shaving tool is in or should be moved into actual engagement with the workpiece. For example, if the work holder is located below and is movable toward and away from the tool holder, the cam is rocked step-by-step and is caused to lift the work holder toward the tool holder in order to move the workpiece into requisite position with respect to the tool. A serious drawback of such method is that the cam cannot block movements of the work holder in a direction toward the tool holder since the cam actually performs the sole function of lifting the work holder without being in a position to limit the extent to which the work holder may move toward the tool holder. In other words, such cam merely controls the maximal distance between the two holders without being capable of determining the minimal distance between the tool and the workpiece. Therefore, and if the gear shaving machine or certain of its parts are caused to vibrate or are subjected to unexpected shocks, the distance between the workpiece and the tool is likely to be reduced below a permissible minimal distance. Such reduction in distance between the workpiece and the tool cannot be counteracted by a cam which is utilized for moving the work holder toward the tool holder or vice versa. While the vibrations or shocks are normally rather small, they can affect the shaving operation since shaving of gears is a work which must be carried out with a high degree of precision. For example, vibrations may cause chatter marks in the flanks of teeth on a shaved gear or a similar workpiece.

Accordingly, it is an important object of the present invention to provide a gear finishing method according to which vibrations, shocks and other undesirable movements of the machine frame and/or of certain of its tool or work-supporting parts cannot influence the finishing operation.

Another object of the invention is to provide a gear finishing method according to which the minimal distance between a finishing tool and a workpiece may be controlled with utmost precision and according to which such minimal distance is maintained under all operating conditions in an extremely simple and reliable manner.

A further object of the invention is to provide a method of determining, maintaining and/or changing the minimal distance between a work holder and a tool holder in all types of gear shaving machines including those which are utilized for crown shaving and/or for so-called immersion shaving.

2

In accordance with my method, the teeth of a first gear-shaped member are shaved by the teeth of a second gear-shaped member in such a way that one member is caused to move rapidly into meshing engagement with the other member, that the distance between the axes of the two members is thereupon reduced gradually whereby the teeth of the second member remove shavings from the teeth of the first member, that the movable member is gradually moved away from the other member when the removal of shavings is completed, and that the movable member is thereupon rapidly returned to its original position in which the teeth of the first member are out of mesh with the teeth of the second member. In many instances, gradual return movement of the movable member is preceded by a comparatively short period during which the speed at which the distance between the two members is being changed equals or is close to zero so that the teeth of the second member may treat the teeth of the first member without actually removing pronounced shavings therefrom in order to insure that eventual markings or stripes are fully removed from the teeth of the first member before the two members are disengaged from each other.

The novel features which are considered as characteristic of the invention are set forth in particular in the appended claims. The improved method itself, however, together with additional features and advantages thereof, will be best understood from the following detailed description of certain specific embodiments with reference to the accompanying drawings, in which:

FIG. 1 is a side elevational view of a machine for rotary crossed-axes shaving of gears and similar workpieces wherein the blocking means which controls the minimal distance between the work holder and the tool holder comprises a specially configurated rotary plate cam, a portion of the machine being broken away to reveal certain parts which drive the blocking cam without any interruptions and which are mounted in the frame and in the work holder;

FIG. 2 is a horizontal section as seen in the direction of arrows from the line II—II of FIG. 1;

FIG. 3 is a top plan view of the machine;

FIG. 3a is a developed view of the blocking cam;

FIG. 3b is a similar developed view of another blocking cam;

FIG. 3c is a developed view of a further blocking cam;

FIG. 4 is a side elevational view of a modified machine which is utilized for crown shaving of gears and similar workpieces, a portion of the machine frame and of the work holder being broken away to reveal the construction of the drive for the blocking means which is identical with the blocking means shown in FIGS. 1 to 3;

FIG. 5 is a part front elevational and part vertical sectional view of the crown shaving machine, the section of FIG. 5 being taken in the direction of arrows as seen from the line V—V of FIG. 4;

FIG. 6 is a side elevational view of a further gear shaving machine wherein the blocking means comprises two spaced blocking elements which are fixed to the work holder and which may be moved into abutment with the tool holder to determine the minimal distance between the axes of the workpiece and the tool, a portion of the work holder being shown in vertical section;

FIG. 7 is a front elevational view of the machine as seen from the left-hand side of FIG. 6;

FIG. 8 is a fragmentary section through a tailstock and a cam-shaped blocking element which is adjustably mounted in the tailstock;

FIG. 9 is a larger-scale fragmentary section through the slip clutch of the drive for the machine of FIG. 7;

FIG. 10 is a section along the line X—X in FIG. 9; and

FIG. 11 an axial section through a worm which is used in the machine of FIG. 7 and which is biased by axially operating spring means.

Referring now in greater detail to the illustrated embodiments, and first to FIGS. 1 to 3, there is shown a gear shaving machine of the knee-and-column type comprising a frame 10 carrying at the top of its column 10a a horizontal plate 11 which supports a swingable tool holder 12, the latter being provided with T-clamps 14 which are slideable in an arcuate T-groove 13 and which enable the tool holder to be fixed to the plate 11 in different positions of adjustment. The holder 12 supports a tool 15 which is rotatable about a horizontal axis and which is driven by an electric motor 16 through a gear reducer 17 or through a suitable transmission (not shown).

The front face of the column 10a is provided with vertical guide means or ways 18 which make right angles with the plane of the plate 11 and which support and guide a work holder including a first slide in the form of a knee 19 in such a way that the slide 19 is reciprocable along the ways 18 in directions upwardly toward and downwardly away from the tool holder 12. The front face of the slide 19 is formed with a vertical dovetailed groove which receives the rail 20 of a second slide 21, and it will be noted that the rail 20 is parallel with the ways 18 to permit the second slide 21 to move with respect to the first slide 19 in directions toward and away from the tool 15. The gear shaving machine is provided with means (not shown) for fixing the slide 21 to the slide 19 in any of a number of positions of adjustment. The slide 21 carries a horizontal pivot pin 22 which makes right angles with the longitudinal extension of the ways 18 and which supports a rotary work table 23 for two work engaging members here shown as tailstocks 24, 25. These tailstocks support a gear-shaped workpiece 26 in the well known manner. By adjusting the angular position of the table 23, an operator may move the axis of the workpiece 26 into parallelism with the axis of the tool 15, or the axis of the workpiece may cross the axis of the tool, depending upon whether the machine of FIGS. 1 to 3 is utilized for shaving of cylindrical workpieces (such as spur gears) or conical workpieces (such as bevel gears). The means for fixing the table 23 in any of several positions of inclination with respect to the slide 21 is not shown in the drawings. It will be noted that the parts 19 to 25 together constitute a composite holder for the workpiece 26 and that this work holder is located at a level below the tool holder 12 and is operatively connected with ways 18 in such a manner that it may reciprocate in a straight path upwardly toward and downwardly away from the tool holder.

The frame 10 supports a horizontal cam shaft 28 which is parallel with the pivot pin 22 and whose forward end carries a blocking means here shown as a detachable plate cam 27. The shaft 28 is driven by an electric motor 29 through a multi-stage or infinitely variable transmission 30 (as shown in German Patents Nos. 810,565 and 953,930) and through a worm drive including a worm 31 driven by the transmission 30 and a worm wheel 32 which is mounted on the cam shaft 28. The rear end of the cam shaft 28 carries two control cams 33, 34 which respectively cooperate with trips of electric switches 36, 35 to regulate the operation of the shaving machine. For example, the switches 35, 36 may be respectively connected in the circuits of electric motors 16, 29 to arrest the gear shaving machine after the cam shaft 28 has completed a full revolution.

The blocking cam 27 cooperates with a roller follower 37 which is rotatably mounted on a horizontal bolt 37a carried by the slide 19 and which tracks the face of the blocking cam so that the extent to which the slide 19 (and hence the workpiece 26) may move upwardly toward the work holder 12 depends on the configuration of the cam 27 which is located above the follower 37. The latter is biased into permanent contact with the face of the cam 27 by an advancing means here shown as a

resilient package of dished springs 38 which are inserted into an upwardly extending blind bore 19a of the slide 19 and which rest on the tip of a regulating screw 39. The screw 39 is axially movable in, but is prevented from rotation with respect to the frame 10. The axial position of the screw 39 may be adjusted by a nut 40 which is rotatably mounted in the frame 10 and which meshes with the screw so that rotation of nut 40 will cause axial displacements of the screw 39 toward or away from the blocking cam 27, depending upon whether the nut 40 is rotated in a clockwise or anticlockwise direction. It will be readily understood that the resilient package 38 may be replaced by a helical spring, by a package of leaf springs, by a hydraulic system, by a pneumatic system or by other advancing means as long as such advancing means can produce requisite force for moving and for maintaining the follower 37 in engagement with the face of the blocking cam 27. The nut 40 may be turned by hand or through a suitable motion transmitting mechanism. For example, the nut 40 may constitute a worm wheel and is then rotated by a worm with which it forms a drive such as the worm drive 31, 32.

The machine of FIGS. 1 to 3 is utilized for carrying out the method of my invention as follows:

In the first step, the operator or operators adjust the position of the tool holder 12 with respect to the plate 11 and the angular position of the table 23 with respect to the pivot pin 22. The axis of the tool 15 is then either parallel with or crosses the axis of the workpiece 26. The blocking cam 27 is in its starting position, i.e., it maintains the slide 19 and the tailstocks 24, 25 at such distance from the tool 15 that the workpiece 26 may be mounted on the table 23. Once the workpiece is properly mounted between the tailstocks 24, 25, the operator starts the motors 16 and 29 whereby the motor 16 drives the tool 15 and the latter may mate with and may rotate the workpiece 26. In other words, the teeth of the tool 15 are immersed or dip into the spaces between the teeth of the workpiece 26 (hence the name "immersion or dipping type of gear shaving"). At the same time, the motor 29 drives the cam shaft 28 and the latter begins to rotate the blocking cam 27 so that the cam permits slight upward movement of the slide 19 which is sufficient to move the workpiece into requisite position in which it is engaged by the tool 15, and the tool removes shavings from the teeth of the workpiece. Since the transmission 30 is adjustable, the operator may cause the cam shaft 28 to rotate at different speeds so that the workpiece 26 may be rather rapidly lifted into operative engagement with the tool 15, whereupon the angular speed of the blocking cam 27 preferably decreases to allow for sufficient time during which the tool 15 remains in shaving engagement with the workpiece.

The configuration of the blocking cam 27 is shown in developed view in FIG. 3a. This cam comprises a lobe 27a whose periphery 27b constitutes the first section of the cam face 27F and which is engaged by the roller follower 37 (under the bias of the advancing means 38) when the machine of FIGS. 1 to 3 is at a standstill. The shaft 28 is assumed to drive the cam 27 in a direction as indicated by the arrow 28a and, when the motor 29 is started, the follower 37 begins to track a second section 27c of the cam face 27F which extends inwardly toward the axis of the shaft 28 (the latter is assumed to be located at a level above the cam 27, as viewed in FIG. 3a) whereby the advancing means 38 compels the work holder 19-25 and hence the workpiece 26 to move upwardly and into meshing engagement with the tool 15. The inclination of the section 27c is rather pronounced so that the workpiece is moved rapidly into meshing engagement with the tool. The arrangement is preferably such that, when the follower 37 has already passed along the first portion 27c' and tracks the right-hand portion 27c'' of the section 27c (as viewed in FIG. 3a), the workpiece is advanced into such close proximity of the tool 15 that the

latter's teeth begin to remove shavings from the workpiece. The section 27c is followed by a section 27d of very slight inclination, i.e., the section 27d may constitute a portion of a substantially cylindrical surface which is concentric with the axis of the cam shaft 28 so that the distance between the workpiece and the tool remains unchanged or is reduced very slightly when the follower 37 tracks the section 27d. During engagement between the section 27d and the follower 37, the teeth of the workpiece complete the shaving of the workpiece, and the section 27d is followed by a further section of 27e of slight negative inclination with respect to the axis of the cam shaft 38. In other words, while tracking the section 27e, the follower 37 causes the workpiece 26 to move downwardly and away from the tool 15, thus enabling the tool to run itself out while the workpiece moves out of compressive engagement therewith. The last section 27f of the cam face 27F has a pronounced negative inclination (i.e., it is inclined in a direction away from the axis of the cam shaft 28 and leads the follower 37 back onto the first section 27b to thereby disengage the workpiece from the tool 15 and to enable an operator to replace the workpiece by a new one.

The transmission 30 may drive the cam shaft 28 in such a way that, when the motor 29 is started, the blocking cam 27 begins to rotate rapidly so that the follower 37 tracks the first portion 27c' of the section 27c at a comparatively high speed, thus enabling the advancing means 38 to rapidly lift the workpiece 26 toward the tool 15. The transmission 30 shifts into a lower speed when the follower 37 reaches the right-hand end of the portion 27c' (as viewed in FIG. 3a) so that the movement of the workpiece toward the tool 15 is slowed down to a degree necessary for maintaining an efficient shaving operation, namely, the workpiece is lifted at a speed which is low enough to insure that the serrated teeth of the tool 15 are not compelled to remove shavings of excessive thickness. When the follower 37 tracks the section 27d, the speed of the cam shaft 28 may be the same as in the preceding operation during which the follower engages the second portion 27c'' of the section 27c. During that stage of the operation when the follower 37 tracks the section 27e, the teeth of the tool 15 may remain in mesh with the teeth of the workpiece 26 so that the latter rotates with the tool while the work holder 19-25 moves slowly downwardly and away from the tool holder 12. Such engagement between the teeth of the workpiece and the tool while the follower tracks the section 27e is advisable because the teeth of the tool are then in a position to remove markings or scratches from the teeth of the workpiece. Such markings can develop during that stage of operation when the tool removes shavings because the work holder is being caused to move toward the work holder to reduce the distance between the axes of the tool and the workpiece.

In the last stage of the operation, the transmission 30 again shifts into high speed and the follower 37 is caused to travel rapidly along the section 27f in order to return into engagement with the lobe 27a of the blocking cam (section 27b) whereby the blocking cam causes the workpiece to descend rapidly away from and out of mesh with the tool 15, and the cam arrests the work holder at such distance from the tool holder which is sufficient to permit convenient removal of the workpiece from the tailstocks 24, 25.

It will be noted that, when the blocking cam 27 completes a full revolution, the tool 15 has completed the shaving of a workpiece and the control cams 33, 34 may arrest the motors 16, 29 while the operator replaces the finished workpiece by a new one.

In accordance with a slight modification which is so obvious that it can be readily comprehended without a separate illustration, the configuration of the blocking cam 27 may be simplified in the following manner:

The face of this cam may consist of three sections,

namely, a first section 27b which surrounds the cam lobe 27a, a second section 27c of positive inclination with respect to the axis of the cam shaft 28, and a third section 27f of negative inclination. Thus, the section 27d of FIG. 3a may form part of the section 27c, and the section 27e may form part of the section 27f. In such instance, the last portion of the section 27c may perform the function of the section 27d in cooperation with the transmission 30 which drives the cam shaft 28 at a speed which is sufficiently slow to insure that the teeth of the tool may properly remove shavings from the teeth of the workpiece. In the zone of transition between the last portion of the section 27c and the first portion (corresponding to the section 27e of FIG. 3a) of the section 27f, the work holder 19-25 then reverses the direction of its movement while the transmission 30 continues to drive the cam shaft 28 at a slow speed so that initial disengagement between the workpiece and the tool is gradual which enables the teeth of the tool to remove eventual markings from the teeth of the workpiece. The last portion of the section 27f on such a modified blocking cam is tracked while the cam shaft 28 is driven at a higher speed so that the workpiece is moved rapidly out of actual mesh with the tool and assumes a position in which it can be removed from the tailstocks 24, 25. In other words, such modified blocking cam is utilized in combination with a transmission which regulates the speed of the cam shaft 28 in a sense to insure that the shaving operation is carried out in the same way as described in connection with FIG. 3a. Thus, while the configuration of the face on the blocking cam is simplified, the various speeds at which the transmission 30 drives the cam shaft 28 must be regulated by a more complicated mechanism.

The rotary blocking cam 27 may be replaced by a so-called wedge cam which moves back and forth and which controls the minimal distance between the workpiece and the tool while performing a linear rather than a rotary movement. If the blocking means is a wedge-like cam, the operative connection between the motor 29 and the blocking means is changed in such a way that the blocking means moves continuously in a linear path and that its cam face may control the position of the slide 19 with respect to the ways 18 in a manner analogous to that described above.

It will be noted that the blocking cam 27 cooperates with the follower 37 of the work holder 19-25 to determine the minimal distance between the work holder and the tool holder 12 against the action of the advancing means 38 so that vibration of the frame 10 or of one or both holders can have no bearings on the minimal axial distance between the tool and the workpiece, particularly during such intervals when the workpiece is actually shaved by the teeth of the tool 15. The principle is the same if the position of the workpiece and of the tool 15 is reversed, i.e., if the workpiece is mounted in the holder 12 and if the tool is mounted in the holder 19-25. The heretofore described feature of the machine resides in the provision of means which blocks a reciprocable holder against excessive movements in a direction toward the fixed holder, regardless of whether the tool is mounted in the reciprocable holder or in the fixed holder.

FIG. 3b illustrates a somewhat different blocking cam 127 whose cam face 127A is very similar to the cam face 27F of the cam 27, excepting that the section 27c is replaced by two mutually inclined sections 127c', 127c''. The remaining sections 27b, 27d, 27e and 27f of the cam face 127F are identical with the corresponding sections of the cam face 27F. The section 127c' is tracked by the follower 37 when the transmission 30 drives the cam shaft 28 at a fixed speed in order to permit rapid advance of the work holder 19-25 toward the tool holder 12. When the follower 37 tracks the section 127c'', the teeth of the tool 15 remove shavings from the teeth of the workpiece, and such removal of shavings continues while the follower tracks the section 27d. When the follower

tracks the section 27e, the teeth of the tool 15 remove markings from the teeth of the workpiece, and the follower 37 rolls along the last section 27f when the workpiece is caused to rapidly return to its original position in which it may be removed from the tailstocks. An important advantage of the cam 127 is that the transmission 30 may drive the shaft 29 at constant speed, i.e., the machine may utilize a greatly simplified transmission because the configuration of the cam 127F by itself insures that the speed at which the workpiece moves toward and away from the tool is regulated in a manner as described in connection with FIG. 3a and that the duration of engagement between the teeth of the workpiece and of the shaving tool is sufficient to insure satisfactory removal of shavings and eradication of any markings which might have remained after the tool has ceased to remove shavings (section 27e).

FIG. 3c illustrates a blocking cam 227 whose face 227F changes its inclination gradually, i.e., without such pronounced transitions as shown between certain sections of the cam face 27F or 127F. The sections 227b, 227c', 227c'', 227d, 227e and 227f of the cam face 227F respectively correspond to the sections 27b, 127c', 127c'', 27d, 27e and 27f of the cam face 127F.

It should be mentioned here that the cam 27, 127 or 227 is equally useful in convenient gear finishing machines of the type described in the introductory part of this disclosure, namely, in which the cam serves as a means for determining the maximal distance between the work holder and the tool holder and wherein the cam cooperates with a follower which is biased by a spring or by another advancing means in a sense to move the work holder away from the tool holder. This will be readily understood since, and insofar as the regulation of the shaving operation is concerned (to wit: by disregarding the feature that the cam may serve as a blocking means which determines the minimal distance between the workpiece and the tool), the cam 27, 127 or 227 will regulate movements of the workpiece into engagement with or away from the tool (or vice versa) if the cam serves as an advancing rather than as a blocking means. For example, all that is necessary is to mount the cam 27 of FIG. 1 at a level below the slide 19 and to mount the resilient package 38 in the slide 19 in such a way that it biases the follower downwardly and into engagement with the face of the cam. In fact, if the cam is mounted in such a way that it controls the maximal distance between the work holder and the tool holder, the package 38 may be omitted altogether and the follower 37 of the work holder 19-25 may rest by gravity on the cam face 27F.

Before proceeding with the description of certain other features of my invention, I will point out the advantages of the method which was described in connection with FIGS. 3a to 3c. Heretofore, it was customary to control movements of the tool into shaving engagement with a workpiece or vice versa by means of a variable speed motor, i.e., it was necessary to shift into different speeds if the operator desired to alter the speed at which the axes of the workpiece and of the tool were moved toward each other. Such operation is time-consuming and the teeth of the tool invariably leave some markings on the teeth of the tool, particularly if the shaving operation is carried out by the immersion process. Attempts were made to improve the operation of such shaving machines by special distribution of shaving edges on the teeth of the tool in a manner as disclosed in copending application Serial No. 158,407 of Fritz Hurth and assigned to the same assignee. While such distribution of shaving edges brings about substantial improvements in the shaving operation, the machine is more complicated because the rate at which the workpiece is moved in stepwise fashion toward the tool or vice versa depends on the distribution of cutting edges on the teeth of the shaving tool.

By providing a movable cam whose rotary or reciprocatory movement is not interrupted while it causes the workpiece to move toward the shaving tool or vice versa,

I provide a very simple and highly satisfactory method of preventing the formation of markings on the teeth of the workpiece. This, and as described in connection with FIGS. 1 to 3, movements of the cam 27, 127 or 227 need not be interrupted at all at the time the cam causes one of the holders to reduce the distance between the axes of the tool and the workpiece. In other words, the cam moves uninterruptedly all the time while the workpiece is being moved toward and while the teeth of the workpiece remain in engagement with and are being treated by the teeth of the tool. In fact, and as explained hereinabove, movements of the cam need not be interrupted at all from the very start and all the way to the end of a shaving operation including movements of the workpiece into and out of mesh with the shaving tool. Therefore, the likelihood that the shaving tool would leave undesirable scratches or other markings on the teeth of the workpiece is very remote, and it was found that the method of my invention actually insures that the tool can treat the teeth of the workpiece to exceptionally high degree of precision finish.

The important feature of my method resides in that the distance between the axes of the workpiece and the tool is being reduced continuously up to the very moment when the shaving operation is completed so that it is not necessary to interrupt the advance of the tool toward the workpiece or vice versa. The speed at which the two gear-shaped members move toward each other may be varied by interposing a transmission in the power line between a constantly driven motor and the cam and/or by imparting to the cam face a configuration which insures that the speed at which the distance between the two gear-shaped members is being reduced is changed whenever necessary to insure that the teeth of the workpiece are shaved to an exceptionally high degree of precision finish.

The reason for reducing the speed at which the two gear-shaped members are being moved toward each other at the time when the shaving operation is about to be or is actually completed is that, otherwise, it would be necessary to immediately reverse the direction of movement when the removal of shavings is completed. Such rapid reversal in the direction of movement of the workpiece with respect to the tool or vice versa would invariably produce some markings on the teeth of the workpiece and, therefore, by utilizing a cam whose face or whose drive means insures that the transition between forward speed and return speed of the movable holder is gradual I provide a method according to which the periods of idleness between consecutive stages of a shaving operation are reduced to zero and wherein the workpieces may be treated to a higher degree of precision finish than in all such gear shaving machines of which I am aware at this time.

In the embodiment of FIG. 3a, gradual transition between forward and return movements of the movable work holder 19-25 takes place when the follower 37 tracks the sections 27d, 27e of the cam face 27F, whereby the speed at which the distance between the axes of the tool 15 and workpiece 26 changes while the follower tracks the sections 27d, 27e is close to zero. This obviously insures that the transition between forward and return movements of the work holder 19-25 is gradual and the tool cannot cause undesirable scratches on the teeth of the workpiece.

I have found that, when a shaving operation is being carried out, it is undesirable to maintain the distance between the workpiece and the tool unchanged for an extensive period of time because the tool then produces so-called zebra stripes in the teeth of the workpiece. In order to avoid the formation of such stripes, my method is preferably carried out in such a way that the interval of time during which the forward or return speed of the movable holder equals zero is very short, that such short interval of zero speed is preceded by an interval (cam section 27d in FIG. 3a) during which the forward speed

of the movable holder is low, and that such short interval of zero speed is followed by an interval (cam section 27e in FIG. 3a) during which the return movement of the holder takes place at low speed. Regardless of whether the gear shaving machine utilizes a rotary plate cam of the type shown in FIGS. 3a to 3c or a movable wedge cam, its cam face is configurated in such a way that the transition between high forward speed (cam face section 27c) and high return speed (cam face section 27f) is always smooth so that zero speed is reached and passed gradually (cam face sections 27d, 27e).

Of course, and as explained hereinabove, the same effect can be obtained even if the transition between the positive and negative inclinations of the cam face is abrupt, as long as the speed at which the cam is moved is regulated in such a way that the forward speed of the movable holder is reduced gradually before it drops to zero speed and that return movement of the movable holder immediately following zero speed is also gradual. This can be achieved by utilizing a transmission which can change the speed of cam movement to compensate for omission of certain cam face sections such as the sections 27d, 27e of the cam face 27f shown in FIG. 3a. However, if the cam face is configurated in a manner as shown in FIGS. 3a to 3c, the cam is capable of regulating the forward and return speeds of the movable holder without necessarily changing the speed of its angular or linear movement.

FIGS. 4 and 5 illustrate a modified gear having machine whose frame 110 comprises a column 110a and a head 110b, the latter mounting an adjustable holder 55 for the tool 115. In contrast to the construction of the machine shown in FIGS. 1 to 3, the modified machine is assembled in such a way that the workpiece 126 is reciprocable in its holder in directions parallel with the axis of the tool 115 and, in addition, the work holder is reciprocable in a straight path in directions toward and away from the tool holder 55. The manner in which the slide 19 is reciprocable along vertical ways provided on the front face of the column 110a is the same as described in connection with FIGS. 1 to 3, and the front face of the slide 19 is again provided with a vertical groove for the rail 20 of a second slide 21 which carries a fixed housing 40 for the vertical shaft of a rotary carriage 41 supporting a reciprocable slide 42 which carries a pivotable base plate 43 for a tiltable table 44. Rocking movements of the table 44 are controlled by a rocking device including an adjustable guide bar 45 which is received between three rollers 46 supported on the table 44 in a manner as described in copending application Serial No. 130,624, of Otto Rogg, assigned to the same assignee. The bar 45 may be fixed to the housing 40 in a number of different angular positions and rocks the table 44 in synchronism with longitudinal displacements of the slide 42.

The table 44 is reciprocated by an electric motor 47 mounted on the housing 40 and by a gear train including two mating spur gears 48 which act as a gear reducer and one of which is directly driven by the output shaft of the motor 47, a pair of mating spur gears 49 which act as a reversing gear, two pairs of mating bevel gears 50, 51, a third pair of mating spur gears 52 one of which drives a horizontal spindle 53, the latter mounted in the carriage 41 and meshing with a spindle nut 54 which is fixed to and which extends downwardly from the slide 42. The adjustable holder 55 enables the tool 115 to assume a position in which its axis crosses the axis of the workpiece 126, the latter mounted in tailstocks 24, 25 carried by the tiltable table 44. The machine of FIGS. 4 and 5 is utilized for crown shaving. If desired, the tailstocks 24, 25 may be mounted on a plate which is then tiltably supported by the table 44. The operation of such crown shaving machines is known and need not be described in greater detail. The tool 115 is driven

by a suitable motor, for example, in a manner as illustrated in FIGS. 1 to 3, and rotates the workpiece 126 when the latter is lifted by the slide 19 into the range of teeth on the tool. At the same time, the motor 47 drives the gear train 48-54 and brings about reciprocatory movements of the workpiece 126 with respect to the tool.

The blocking means 27 and the advancing means 38 in the gear shaving machine of FIGS. 4 and 5 are identical with the corresponding blocking and advancing means of FIGS. 1 to 3a excepting that one of the switches 35, 36 may control the motor 47. The blocking cam 27 again cooperates with the roller follower 37 and operates against the action of the advancing means 38 to limit movements of the workpiece 126 in a direction toward the tool 115. Any movements of the workpiece in a direction away from the tool are possible only by overcoming the bias of the advancing means 38. The composite tool holder of the machine shown in FIGS. 4 and 5 includes the parts 19-21, 24, 25 and 40-44. The means for driving the blocking cam 27 is the same as in the machine of FIGS. 1 to 3, and the face of the blocking cam may assume a configuration as shown in FIG. 3a, 3b or 3c.

In the gear shaving machine of FIGS. 4 and 5 in which the workpiece is reciprocated with respect to a rotating gear-shaped tool, the formation of zebra stripes is fully avoided if the face of the blocking cam 27 assumes a configuration as shown in FIGS. 3a to 3c. Such cam insures that the teeth of the workpiece and of the tool are slightly separated before the workpiece is rapidly returned to its original position of disengagement from the tool 115. Heretofore, such crown shaving machines were operated in such a way that the workpiece was caused to reciprocate with respect to the revolving tool after the latter has completed the actual shaving operation in order to make sure that the tool would remove all stripes from the teeth of the workpiece. Such additional reciprocation of the workpiece consumes much time and reduces the output of the crown shaving machine. In accordance with my invention, removal of eventual stripes from the teeth of a shaved workpiece takes place at the time when the workpiece is moved gradually away from the tool or vice versa.

FIGS. 6 and 7 illustrate a different gear shaving machine which comprises a frame 61 having a head 61b for an adjustable tool holder 62. The machine of FIGS. 6 and 7 is of the vertical knee-and-column type, and the holder 62 enables the tool 215 to assume a number of different positions with respect to the workpiece 226. The means for driving the tool 215 is known in this art and, therefore, is not illustrated in the drawings.

The column 61a of the frame 61 supports a vertically reciprocable slide 63 which is movable along vertical ways 64. The slide 63 supports a work table 65 which is tiltably about a horizontal pivot pin 66, the latter making right angles with the longitudinal extensions of the ways 64. The table 65 carries two tailstocks 67, 68 for the workpiece 226, and the arrangement is preferably such that the axis of the workpiece 226 crosses the axis of and is driven by the tool 215 when the machine is in operation. The extent to which the table 65 may be rocked about the pivot pin 66 is regulatable by two screws 69, 70 which are mounted on the slide 63 and whose tips are located beneath the table 65 at the opposite sides of the pivot pin 66. As a rule, the play of the table 65 with respect to the screws 69, 70 is rather small.

The tailstocks 67, 68 respectively support substantially prismatic blocking elements 71, 71a, and portions of these blocking elements extend into upwardly opening cutouts or recesses provided in the respective tailstocks to be retained in requisite position by clamping screws 72. The elements 71, 71a are preferably located at the opposite sides of and in close or immediate proximity of the tool 215 to insure that the relative position of the axis of the workpiece 226 with respect to the tool axis

11

remains unchanged irrespective of elastic deformation of the work and tool holders. The slide 63 is reciprocable along its ways 64 by a vertical spindle 73 which is mounted on the base 61c of the frame 61 and which may be driven by an electric motor 74 or by a handwheel 75 through a suitable transmission accommodated in the interior of the slide 63. Since the motor 74 or the handwheel 75 must advance the blocking elements 71, 71a into abutment with a fixed part, i.e., with the tool holder 62 or with another component which is rigid with the frame 61, the transmission mounted in the slide 63 preferably comprises a suitable slip clutch 74a, i.e., a friction clutch or the like which permits the motor 74 or the handwheel 75 to rotate with respect to the spindle 73 when the blocking elements 71, 71a prevent further ascent of the work holder. Combined with that part of the slip clutch which slides with respect to the motor is a gear member 85 which drives a worm gear 88 through a gear 86 which is preferably shiftable, and through a worm 87. The worm gear 88 is a spindle nut in mesh with the spindle 73. FIG. 9 shows on a larger scale a section through the slip clutch and illustrates that the slidable gear member 85 is provided with one or more cam means 89. A switch 91 provided on a member 90 of the clutch is connected with the motor. The switch sends an impulse as soon as one of the cam means 89 operates a control member 92 mounted in the member 90. Thus, the switch 91 will at once switch off the drive (motor 74) for the slide 63 or will switch on a time-lag relay which will switch off the motor 74 after a predetermined period of time and eventually initiate return movement as soon as the relative movement between motor 74 and the gear member 89 is terminated. In order to avoid the provision of a slip clutch for damping the impact the worm 87 may be axially shiftable and may be elastically supported (FIG. 11) in a manner as disclosed in German Patent 1,108,543 or in U.S. Patent 2,945,925. If desired, both methods may be combined. The worm 87 can operate a switch 87a.

The machine of FIGS. 6 and 7 need not comprise means for reciprocating the workpiece 226 with respect to the tool 215 because it is assumed that the axial length of the tool is sufficient to engage the workpiece along the full length thereof (see FIG. 7). In addition, the tool 215 is assumed to be a hyperboloidal gear so that the shaving operation may be carried out on the so-called dipping or immersion principle.

The distance between the axes of finished workpiece 226 and tool 215 is determined by the dimensions of exchangeable blocking elements 71, 71a. If the distance between the surfaces 76, 77 on the tailstocks 67, 68 (which abut against the undersides of the elements 71, 71a) and the corresponding surfaces 78, 79 (which abut against the upper sides of the elements 71, 71a) is the same, both blocking elements are of identical height provided, of course, that the workpiece 226 is a cylindrical spur gear. If the workpiece is a bevel gear, the height of one blocking element exceeds the height of the other blocking element so that the axis of the workpiece may be properly inclined with respect to the axis of the tool 215. Each blocking element may consist of several sections which may be separated from each other when it becomes necessary to reduce the minimal distance between the tool and the workpiece.

The machine of FIGS. 6 and 7 is used for carrying out my improved method as follows:

It is assumed that the workpiece 226 is a cylindrical spur gear. In the first step, the slide 63 is moved downwardly (either by starting the motor 74 or by manually operating the wheel 75) in order to permit insertion of the workpiece 226 between the tailstocks 67, 68. The screws 69, 70 are adjusted in such a way that there remains some play between their tips and the table 65 which is sufficient to permit proper adjustments in the position of the table depending on the type of blocking elements 71, 71a momentarily used in the machine. In

12

the next step, the elements 71, 71a are clamped in the recesses of the respective tailstocks so that they may determine the shortest distance between the axes of the workpiece 226 and tool 215 as soon as their upper sides 5 engage the surfaces 78, 79. Once the workpiece 226 and the blocking elements 71, 71a are properly mounted in the tailstocks 67, 68 the drive for the tool 215 is started to rotate the tool, and the motor 74 is also started to move the slide 63 in upward direction and to thereby advance the workpiece into mesh with the tool. Upward movement of the workpiece is terminated when the blocking elements 71, 71a abut against the surfaces 78, 79 and the height of these blocking elements is selected in such a way that the teeth of the tool 215 remove shavings 10 from the teeth of the workpiece when the blocking elements engage the holder 62. The maximal distance between the holder 62 and the slide 63 need not exceed the minimal distance at which the workpiece may be conveniently removed from the tailstocks 67, 68. 15 Of course, at the time the blocking elements 71, 71a move into actual abutment with the tool holder 62, there develop some compressive stresses between the tool and the workpiece, but such stresses diminish at the same rate at which the tool removes shaving from the workpiece 20 so that all stresses are eliminated upon completion of the shaving operation. The slip clutch in the aforementioned transmission between the motor 74 and spindle 73 enables the motor or the handwheel to bias the blocking elements 71, 71a into constant abutment with the tool holder 62. Such bias of the parts 73, 74, 74a eliminates any play between the tool holder 62 and the work holder 63-68. It will be noted that the parts 73, 74, 74a constitute an advancing means for the work holder 63-68 whose function is equivalent to the function of advancing 25 means 38.

The machine of FIGS. 6 and 7 may be readily modified in a number of ways without departing from the scope of my invention. For example, the workpiece 226 may reciprocate with respect to the tool 215 in a manner analogous to that described in connection with FIGS. 4 and 5. In such instances, prismatic blocking elements 71, 71a are preferably replaced by rollers to reduce friction with the tool holder when the workpiece and its holder are caused to reciprocate with respect to the tool holder. 45 Furthermore, the blocking elements 71, 71a may assume the form of eccentric cams which are adjustably mounted in the tailstocks or in another part of the work holder so that, merely by angularly displacing the cams, an operator may convert the machine for shaving of differently 50 configured or dimensioned workpieces. If necessary, such cams may be adjusted in the course of a shaving operation in order to change the minimal distance between the workpiece and the tool in accordance with a predetermined work schedule which may be analogous 55 with the work schedule controlled, for example, by the blocking cam 27 of FIG. 3a. FIG. 8 shows a tailstock 167 which is provided with a recess 167a for an eccentrically mounted blocking element in the form of a plate cam 171. This cam is supported on a rotary eccentric shaft 171A. The position of the eccentric shaft can be regulated by means of a worm gear 172 and a worm 172a. The latter can be driven either manually or by a motor (not shown). The motor can be automatically 60 controlled according to a program which corresponds 65 to that described in connection with FIGS. 3a, 3b, 3c. To arrest the eccentric shaft, a clamp 172b may be provided. In addition to this, a graduated scale as well as a pointer 172c may be provided to enable the operator to read the turning angle. The pointer may be mounted on the worm gear or on the worm. The cam is rotatable with the shaft 171A and may be arrested in any 70 of an infinite number of positions by the clamp 172b which is mounted in the tailstock 167. The tailstock may be provided with a graduated scale and the cam 171 75 may be provided with a pointer to facilitate its adjust-

ment if the machine is converted for treatment of different workpieces. The other tailstock (not shown in FIG. 8) is combined with a second blocking cam which is identical with the cam 171.

The blocking cam or cams may be combined with the spindle 73, or the upper end of this spindle may assume the shape of a cam to insure gradual transition between forward and return movements of the workpiece.

Without further analysis, the foregoing will so fully reveal the gist of the present invention that others can, by applying current knowledge, readily adapt it for various applications without omitting features that, from the standpoint of prior art, fairly constitute essential characteristics of the generic and specific aspects of this invention and, therefore, such adaptations should and are intended to be comprehended within the meaning and range of equivalence of the following claims.

What is claimed as new and desired to be secured by Letters Patent is:

1. A method of shaving the teeth of a first gear-shaped member by engagement with the teeth of a second gear-shaped member, comprising a first step of rotating one of said members; a second step of continuously and gradually reducing the distance between said members to intermesh the teeth thereof whereby said one member rotates the other member and the teeth of said second member remove shavings from the teeth of said first member; and a third step of continuously and gradually increasing the distance between said members with a gradual transition from said second step to said third step.

2. A method of shaving the teeth of a first gear-shaped member by engagement with the teeth of a second gear-shaped member, comprising the steps of supporting said members in such a way that the axis of said first member crosses the axis of said second member; rotating one of said members about the axis thereof; and continuously and gradually reducing the distance between the axes of said members first at a higher speed to rapidly intermesh the teeth thereof whereby said one member drives the other member and thereupon at a reduced speed whereby the teeth of said second member remove shavings from the teeth of said first member.

3. A method of shaving the teeth of a first gear-shaped member by engagement with the teeth of a second gear-shaped member, comprising the steps of supporting said members in such a way that the axis of said first member crosses the axis of said second member; rotating one of said members about the axis thereof; continuously reducing the distance between the axes of said members to intermesh the teeth thereof whereby the teeth of said second member remove shavings from the teeth of said first member; thereupon maintaining the distance between the axes of said members at a substantially constant magnitude while the teeth of said second member remain in mesh with and remove from the teeth of said first member any markings which might have developed during shaving of said first member; and thereupon continuously increasing the distance between the axes of said members, first at a lesser speed and thereupon at a higher speed, until the teeth of said members are out of mesh with each other.

4. A method of shaving the teeth of a first gear-shaped member by engagement with the teeth of a second gear-

shaped member, comprising the steps of supporting said members in such a way that the axis of said first member crosses the axis of said second member; rotating one of said members about the axis thereof; and continuously reducing the distance between the axes of said members first at a higher speed to intermesh the teeth thereof whereby the teeth of said second member remove shavings from the teeth of said first member, and thereupon at a reduced speed so that the teeth of said second member continue to remove shavings from the teeth of said first member.

5. A method of shaving the teeth of a first gear-shaped member by engagement with the teeth of a second gear-shaped member, comprising the steps of supporting said members in such a way that the axis of said first member crosses the axis of said second member; rotating one of said members about the axis thereof; continuously reducing the distance between the axes of said members first at a higher speed to intermesh the teeth thereof and thereupon at a reduced speed whereby said one member rotates the other member and the teeth of said second member remove shavings from the teeth of said first member; thereupon maintaining the distance between the axes of said members at a substantially constant value whereby the teeth of said second member continue to mesh with and to treat the teeth of said first member; and continuously increasing the distance between the axes of said members first at a lesser speed and thereupon at a higher speed until the teeth of said members are out of mesh with each other.

20 6. A method of shaving the teeth of a first gear-shaped member by engagement with the teeth of a second gear-shaped member, comprising the steps of supporting said members in such a way that the axis of said first member crosses the axis of said second member; rotating one of said members about the axis thereof; continuously reducing the distance between the axes of said members first at a higher speed to intermesh the teeth thereof whereby the teeth of said second member remove shavings from the teeth of said first member and thereupon at a greatly reduced speed while the teeth of said second member continue to mesh with and to treat the teeth of said first member; thereupon continuously increasing the distance between the axes of said members first at a lesser speed and thereupon at a higher speed until the teeth of said members are disengaged from each other.

25 7. A method of crown shaving as set forth in claim 6, further comprising the step of reciprocating one of said members in the axis direction thereof.

30 8. A method as set forth in claim 7, further comprising the step of rocking said one member about an axis making right angles with the direction of reciprocatory movement of said one member.
